(57) **CLAIM**

The ornamental design for a vehicle suspension assembly, as shown and described.

DESCRIPTION

FIG. 1 is a top, front, right-side perspective view of a vehicle suspension assembly;

FIG. 2 is a right-side view thereof;

FIG. 3 is a left-side view thereof;

FIG. 4 is a back view thereof;

FIG. 5 is a front view thereof;

FIG. 6 is a top view thereof;

FIG. 7 is a bottom view thereof;

FIG. 8 is a top, front, right-side perspective view that includes disclaimed environment of the vehicle suspension assembly;

FIG. 9 is a front view thereof; and,

FIG. 10 is a right-side view thereof.

The dashed broken lines depict portions of the vehicle suspension assembly that form no part of the claimed design. The dot-dashed broken lines represent boundaries of the claimed vehicle suspension assembly and form no part of the claimed design.

1 Claim, 10 Drawing Sheets
